MOUNTING FOR GUNS AND THE LIKE

Marcel Jules Odilon Lobelle, Langley, and Edmund Voss, Hayes, England, assignors to The Fairey Aviation Company, Limited, Hayes, England

Application May 10, 1937, Serial No. 141,852
In Great Britain December 7, 1935

5 Claims. (Cl. 89—37.5)

This invention relates to mountings for guns, and the like, for use on aircraft, motor boats, and ships, and in similar positions.

5 Collapsible gun or similar mountings are known which comprise a toothed sector pivotally mounted on a transverse axis, a gun-carrying arm pivotally mounted relative to said sector on an axis which is fore and aft when the sector is upright, and means for locking said arm to said sector in its angularly adjusted positions.

In accordance with the present invention, and in order to compensate for the weight of the gun when said arm is swung to one side or the other of its midposition, a suitably guided compression spring is mounted on the sector, which spring abuts against the lower ends of two levers pivoted on the sector, the upper ends of said levers being adapted to lie in the path of said arm or a part carried thereby or movable therewith, and, when engaged thereby, to transmit the weight (or a part of the weight) of the gun to said spring from that end of the spring on the side towards which the gun is moved. If desired, a tension spring may be employed, if 25 the levers be arranged accordingly.

In order that the continuity of the surface of the aircraft, motor boat or the like may be preserved, when the improved gun mounting is in its "stowed" position it may be arranged within a cylindrical or similar body of circular, or mainly circular, cross-section, rotatable on an axis parallel, or substantially parallel, with the adjacent part of the surface of an aircraft, motor boat or the like, and adjacent to an aperture in said surface; part of said body being adapted, when said mounting is in its "stowed" position, to close said aperture by constituting a portion of said surface, whilst, when said body is turned 40 through half a revolution, said aperture is opened and the collapsible mounting may be extended to its "exposed" position.

The invention is particularly suitable for use in connection with a machine gun on an aircraft and will be described with reference thereto by way of example. In the accompanying drawings, Figures 1, 2 and 3 are fragmentary diagrammatic side elevations illustrating one form of the invention, the gun and gun carriage being 45 shown in different positions; Figures 4 and 5 are detail end views of the gun carriage as seen from the left of Figures 1 and 2 respectively, the gun and its collapsible mounting being omitted; Figure 6 is a similar view to Figure 5 but 55 showing the gun and its collapsible mounting in

a laterally extended position, and Figures 7, 8 and 9, are enlarged detail views.

Mounted in brackets *a a* on a horizontal axis and adjacent to an opening at the upper part of the fuselage *b* of an aeroplane and near the tail end thereof is a so-called barrel *c* in the form of a truncated cone having a longitudinal slot *d* extending rearwardly from its larger or front end, trunnions for said barrel being arranged at each end of the barrel *c*. The trunnion at the rear end is carried by one or more radial arms such as *e*, Figures 4 and 5.

Within the barrel *c* and diametrically opposite the slot *d* is arranged a collapsible gun mounting comprising a toothed sector *f* pivotally mounted 15 on a transverse axis at *f'*, a gun-carrying arm *g* pivotally mounted relatively to said sector *f* on a fore and aft axis at *g'* and means for locking the arm *g* to the sector *f* in its angularly adjusted positions. The gun-carrying arm *g* forms part of 20 a parallelogram, the sides of which are pivoted together at the corners of the parallelogram so that as said arm *g* is swung about its fore and aft axis at *g'* a median longitudinal plane of a gun *h* carried thereby will always remain vertical, whilst, 25 when the toothed sector *f* is swung about its transverse axis at *f'* the gun-carrying arm *g* and its associated parts move as one therewith.

The parallelogram above mentioned is constituted by the gun-carrying arm *g* which is bifurcated at its lower end and straddles the sector *f*, a second arm *j*, Figure 6, consisting of a pair of links arranged side by side, see Figure 3, pivoted to the sector *f* on a fore and aft axis as at *j'*, the portion of the sector *f* lying between the pivotal axes *g'* and *f'*, and a corresponding member *k* pivoted to the gun-carrying arm *g* and lying between the pair of links forming the arm *j*, at the ends of said arms *g* and *j* remote from said pivotal axes *g'* and *j'*. Said member *k* is integral with a 40 short spindle *m*, Figure 3, and carries a socket *n* in which a pintle *o* is mounted on a vertical axis at the upper end of which the gun *h* is pivoted on a horizontal axis, thus permitting universal movement of the gun *h* about the gun-carrying arm *g*. 45 In order to compensate for the weight of the gun *h* when said arm *g* is swung to one side or the other of its midposition relatively to the sector *f*, there is mounted on the latter a slotted tube *p* which constitutes a guide for a compression 50 spring *q* abutting against the lower ends of two levers *r r* pivoted on the sector *f*, the upper ends of said levers *r r* lying in the path of a fin or rib *s* on the arm *g* and, when the one or the other of said levers *r r* is engaged by said fin or rib *s*, 55

the weight (or a part of the weight) of the gun *h* is transmitted to said spring *q* from that end of the spring at the side towards which the gun is moved, the inturned end of the tube *p* at the 5 other side, acting, for the time being, as a fixed abutment.

In order that the sector *f* and gun-carrying arm *g* may be supported when raised from a normal horizontal (Figure 2) to a vertical (Figure 3) 10 position, an upwardly-breaking knuckle-jointed strut *t*, *u*, is provided in rear thereof, see Figures 3 and 9, being pivotally connected as at *t'* with said arm *g* through subsidiary arms *v* *v* integral with the latter, and with the barrel *c*, 15 as at *u'*, the arrangement being such that the knuckle joint between the strut elements *t*, *u*, passes its dead centre position when said parts are so raised. In order to limit the extent to 20 which the elements of the strut *t* *u* may move beyond the dead centre when said parts are so raised, in order to break the joint when the strut *t* *u* is to be collapsed to allow the sector *f* and gun-carrying arm *g* to move about the transverse axis at *f'*, from the vertical to the horizontal 25 position and in order to secure said parts in the horizontal position, there is pivotally mounted in the barrel *c* a hook *w* Figures 8 and 9, adapted (a) to constitute a stop for the contiguous ends of the elements *t* *u*, of the strut just after they 30 have passed their dead centre position see Figure 9, (b) to act as a cam, when turned, to force said ends through their dead centre position to enable the knuckle joint to break, and (c) to engage a pin *x* on a lug *y* on the gun-carrying arm *g* when 35 the latter is in its horizontal position (see Figure 8) and thus hold said arm *g* and its associated parts, including the gun *h*, in that position. This hook *w* is mounted on a spindle *x'* with a lever *y'* connected through a link *z* with an operating lever *21* pivotally mounted as at *22* in a 40 convenient position on the barrel *c*.

The barrel *c* itself forms, as nearly as circumstances permit, a continuation of the surface of the fuselage *b* of the aeroplane, and is provided 45 with means whereby it may be turned through half a revolution and locked in either of its extreme positions. For instance, as shown in Figures 4 and 5, hooks or lugs such as *23* on the barrel *c* may be arranged alternatively to engage 50 a stop *24* on the fuselage *b* and a spring influenced detent *25* pivoted on the stop *24* may engage openings such as *26*, Figure 4, teeth or the like on the barrel *c*.

Normally, the gun *h* and its mountings are collapsed into the barrel *c* and locked therein, and the slot *d* in the barrel lies at the bottom thereof, that is to say the gun and its collapsed mounting occupy an inverted position as shown in Figure 1, but, for use, the barrel *c* is turned through half a 55 revolution by means of a handle *27* on the radial arm *e* at the front end of said barrel, and locked, by the detent *25*, in the position shown in Figure 2. The mounting is released by operating 60

the lever *21* to actuate the hook *w*, and is extended by turning the sector *f* and its associated parts about the transverse axis at *f'* so that the gun *h* passes through the slot *d* in the barrel *c* to its "exposed" position, as shown in Figure 3. 5

The gun-carrying arm *g* is locked to the sector *f* in its angularly adjusted positions by means of a detent *28* (Figure 7), pivoted to a lug *29* on said gun-carrying arm and actuated through Bowden-mechanism *30*, *31* by means of a lever *32* disposed 10 adjacent the handle *33* of the gun *h*.

We claim:

1. A collapsible mounting for a gun and the like comprising a movable toothed sector pivotally mounted on an axis in the plane of said sector, a gun-carrying arm pivotally mounted on said sector on an axis which is perpendicular to said first axis, means for adjustably locking said arm to said sector, two levers secured to said mounting, the upper ends of said levers being 20 adapted to engage said arm, spring means, the lower ends of said levers engaging said spring means, and at least one of said levers transmitting the moving weight of said gun to said spring means. 25

2. A mounting as in claim 1, an upwardly-breaking knuckle-jointed strut secured to said gun-carrying arm, and means for passing said knuckle joint by its dead center position on moving said gun to said upright position. 30

3. A mounting as in claim 1, an upwardly-breaking knuckle-jointed strut secured to said gun-carrying arm, means for passing said knuckle joint by its dead center position on moving said gun to said upright position, a pivotally mounted 35 hook, means for moving said hook to constitute a stop for the contiguous ends of the elements of the knuckle-jointed strut just after they have passed their dead center position and to act as a cam to force said ends through their dead 40 center position to enable the knuckle joint to break, and means engageable with said hook to lock said gun-carrying arm in lowered position.

4. A mounting as in claim 1, a substantially cylindrical hollow body rotatable around its longitudinal axis, a longitudinally extending slot in said body, and means for projecting said gun through said slot when said sector is in upright position. 45

5. A mounting as in claim 1, a second arm 50 parallel to said gun carrying arm, pivot means securing one end of said second arm to said sector, a member pivotally joining the other ends of said second arm and gun carrying arm to form therewith and with said sector a parallelogram, 55 and gun carrying means, supported by said gun carrying arm and fixed with respect to said member, for maintaining a gun attached thereto in upright position throughout movements of said gun carrying arm. 60
